CASING HEAD

James B. Wrigley, Tulsa, Okla., assignor to International Supply Company, Tulsa, Okla., a corporation of Delaware

Application May 25, 1937, Serial No. 144,729

6 Claims. (Cl. 166—14)

The present invention relates to casing heads for oil wells and has particular reference to improved casing heads which comprise combinations of tubing hangers, pumping T's and stuffing boxes.

An object of this invention is to provide an improved casing head which will be simpler in construction and cheaper to manufacture than those heretofore used.

10 A particular object is to provide a form of casing head in which the pumping T, which is the well head fitting from which well fluid is discharged by the ordinary oil well pump, is combined with the tubing hanger and the polish rod stuffing box to form a unitary device which can be quickly and easily mounted at the top of an oil well casing and which will be shorter in overall length than combinations heretofore used and will, therefore, occupy less space and be cheaper 20 to construct.

Another object is to provide an arrangement of stuffing box and pumping T which will permit flexing of the polish rod during the pumping operation without deleterious effect of such flexing on the stuffing box packing.

Other objects and advantages of the invention will be apparent from the following description when read in conjunction with the accompanying drawing which illustrates one particular form of 30 the new invention.

In the drawing wherein like numbers indicate the same parts in the various figures,

Fig. 1 is a front partially sectional elevation of the casing head of this invention showing the general assembly of the various parts of the device.

Fig. 2 is a transverse section taken along line 2—2 of Fig. 1.

Fig. 3 is a vertical sectional view of a modified form of the invention.

40 Fig. 4 is a sectional elevation of the lower portion of Fig. 1 taken between the lines 4—4 of Fig. 1 and at right angles to the sectional portion of Fig. 1.

Fig. 5 is a partially sectional view in perspective of the stuffing box sleeve.

Referring to the drawing, the casing head of this invention comprises a combination structure consisting of a tubing hanger 5 on which is mounted a pumping T 6 and a stuffing box 7 mounted on the pumping T 6. These elements are in vertical alignment with respect to each other and are held together into a unitary structure by means and in a manner to be more fully described hereinafter.

55 Tubing hanger 5 comprises a hollow body por-

tion 8 internally threaded at its lower end for engagement with the upper end of a string of casing 9. Mounted within casing 9 is a string of tubing 10, the upper end of which extends through the interior of body portion 8 and for a short distance therebeyond. Mounted in the upper end of body portion 8 are the usual slips 11 which support tubing 10. Slips 11 are wedge shaped tapering from top to bottom and the upper interior wall of body 8 is tapered in a complementary manner to hold the slips against tubing 10. On a level with the top of slips 11, the upper end of body 8 is cut out to form an annular shoulder 12 and an upstanding circular lip 13. Composition packing 14 is positioned on slips 11 and rests on shoulder 12 and is adapted to be compressed into tight engagement with tubing 10 and lip 13 thus sealing body 8 against the passage of well fluids flowing through the annular space between casing 9 and tubing 10. A 20 vent opening 15 communicating with the interior of casing 9 is provided through the wall of body 8 below slips 11 to permit discharge of well fluids from the space between the tubing and casing.

Lip 13 forms an annular flange 16 fitted with 25 apertured ears 16a for receiving bolts 17 when attaching to the tubing hanger the other portions of the device to be later described. It will be recognized that the tubing hanger above-described is of a more or less conventional design. 30

Pumping T 6 consists of a vertically disposed hollow member 18 having a lower portion 19, an upper portion 20, and an intermediate portion 21. The bore 22 of the portion 19 has a diameter somewhat larger than the outer diameter of tubing 10 and permits placing the portion 19 of the T freely over the end of tubing 10. When placed over tubing 10, the lower end of the portion 19 rests on packing 14 within the confines of lip 13. Surrounding the lower end of the portion 19 is an annular flange 23 having apertured ears 24 which register with ears 16a of the tubing hanger flange. Bolts 17 extend through ears 24 and 16a and by tightening nuts 17a, T 6 and tubing hanger 5 are drawn together and the lower end of the portion 19 acts as a gland to compress packing 14 and thereby "pack-off" between casing 9 and tubing 10.

The bore 25 of the portion 20 is somewhat larger in diameter than the bore 22 and terminates 50 at its lower end in an annular shoulder 26 which is preferably hollowed out to form a substantially parti-spherical socket, the function of which will be later described. The upper end of the portion 22 is also surrounded externally by a flange 55

27 fitted with apertured ears 28. The intermediate portion 21 constitutes a flow line extending outwardly from the bore 22.

Stuffing box 7 consists of a sleeve 29 which is tubular in form and has external threads 30 at one end and, at the other end, an annular flange 31 which extends laterally beyond the inner and outer walls of sleeve 29 forming annular shoulders 32 and 33 respectively within and without the sleeve. The lower face of flange 31 is tapered or parti-spherical and is adapted to contact shoulder 26 within bore 25 of arm 20 and to form a ball-and-socket joint therewith. Sleeve 29 surrounds a polish rod 34 which is adapted to reciprocate in tubing 10. A central passageway 35 through flange 31 is sufficiently large to permit free reciprocation of rod 34 therethrough and composition packing 36, held between gland rings 37, is mounted in the annular space between polish rod 34 and the interior wall of sleeve 29, the lower gland ring 37 resting on shoulder 32. A follower nut 38, fitted with handles 39, is threadedly engaged with threads 30 of sleeve 29 and by turning of nut 38, the same acts to press down upon the upper gland ring 37 which in turn compresses packing 36 and provides means for "packing-off" of the polish rod 34. Other composition packing 40, which is preferably soft rubber packing, is placed in the annular space between the sleeve 29 and the wall of bore 25 and rests on shoulder 33. A packing gland 41 surrounds the exterior of sleeve 29 and is spaced therefrom by a space 41a and one end of gland 41 rests on packing 40. The opposite end of gland 41 has a laterally extending annular flange 42 fitted with ears 43 having apertures 44 which are adapted to register with the apertures in ears 28 of flange 27. Bolts 45 extend through apertures 44 and the registering apertures in ears 28 and tightening of nuts 46 thereon acts to unite stuffing box 7 with T 6 and at the same time to compress packing 40 and thus "pack-off" between sleeve 29 and bore 25 of arm 20.

In assembling the device, body 8 of the tubing hanger is screwed onto casing 9 and slips 11 are dropped into place within body 8 engaging tubing 10. Packing 14 is then placed about the tubing and positioned upon the top of slips 11 and shoulder 12. The pumping T 6 is then slipped over the open end of tubing 10 and into contact with packing 14. Bolts 17 are then slipped through ears 16a and 24 and nuts 17a are then adjusted to draw T 6 into operative engagement with the tubing hanger and thereby compresses packing 14 to pack off between the tubing and casing. At this time, the open end of tubing 10, which protrudes into the interior of pumping T 6, will register with the passageway through member 21 of the T, thus permitting discharge of well fluids from the tubing through member 21 to external receivers, not shown.

Since polish rod 34 is in place in tubing 10, it will be readily understood that T 6 is slipped over the upper end of polish rod 34 in placing the T over the open end of the tubing.

Sleeve 29 of the stuffing box is then slipped over the upper end of the polish rod and inserted into bore 25 of the portion 20 of the pumping T to bring the ball surface of flange 31 into engagement with shoulder 26. Lower gland ring 37 is then slipped over rod 34 and brought to rest within sleeve 29 on shoulder 32 and packing 36 is then placed within sleeve 29 and about rod 34 and followed by upper gland ring 37. Packing 40 is then placed in the annular space between

the exterior of sleeve 29 and the wall of bore 25, this packing resting upon shoulder 33. Packing gland 41 is then placed about sleeve 29 and in contact with packing 40 and ears 43 and apertures 44 are brought into registration with ears 28 of T 6. Bolts 45 are then slipped through apertures 44 and ears 28 and nuts 46 are adjusted to draw gland 41 into compressive contact with packing 40 and, at the same time, to operatively connect stuffing box 7 to T 6. Gland nut 38 is then slipped over rod 34 and screwed up on threads 30 of sleeve 29 forcing upper gland ring 37 into compressive contact with packing 36 and completing the assembly of the casing head.

Reciprocation of polish rod 34 during the pumping operation produces a slight flexing or bending from the true vertical of the upper portion of the rod, as is well known in this art, and as is exaggeratedly indicated by the sloping center line shown in Fig. 1. If stuffing box 7 were maintained rigidly in the vertical position on pumping T 6, this bending of polish rod 34 would cause undue wear of packing 36 or scoring of rod 34. To obviate this difficulty, the ball-and-socket joint of this invention, formed by flange 31 and shoulder 26, permits pivotal movement of stuffing box 7 about this joint in accordance with the bending of rod 34. One off-center position of rod 34 is shown in dotted lines in Fig. 1 to illustrate the manner in which the ball-and-socket joint functions to meet this end, the off center position of the rod and flange 31 being shown in full lines and the normal position in dotted lines. When rod 34 bends and sleeve 29 moves in the direction of this bending movement, packing 40 will be compressed and will expand laterally between sleeve 29 and bore 25 in accordance with the direction of movement of rod 34. Gland 41 will remain substantially stationary and the movement of sleeve 29 with the bending of rod 34 will take place within the confines of space 41a.

When constructed in accordance with the above described arrangement, the casing head of this invention will have an over-all height which is several inches shorter than equivalent combinations heretofore used and the new casing head can, therefore, be manufactured at considerable saving in cost over former types and will occupy less space over the well head as well as being more easily and quickly assembled on the well casing.

It will be understood that various modifications and alterations may be made in size, form and arrangement of the various details of the device of this invention. For example, as shown in Fig. 3, the tubing hanger 5a, instead of having a female connection as illustrated above for mounting on the casing, may have a male connection 8b threaded externally for engaging the internal threads of casing 9a. Packing 14, instead of being placed directly upon the slips, may be separated therefrom and a metal spacing ring 14b may be provided between the packing 14 and slips 11a, said ring forming a shoulder arranged in the bore of the tubing hanger above the slips 11a for supporting the packing. A vent opening 15a communicating with the interior of the casing is provided through the wall of the tubing hanger, and in order to permit a well fluid traveling between the tubing 10 and the casing, to reach the opening, the slips may be provided with channels 11b, such as are shown in the patent to Wigle No. 1,863,890, dated June 21, 1932.

The pumping T 6 in either form of the invention

tion may be a cross fitting instead of a T-shaped fitting, with the flange 31 of the stuffing box resting on the shoulder 26 within said fitting.

What I claim and desire to secure by Letters 5 Patent is:

1. In combination, a well pipe, a tubing hanger secured to the upper end of the well pipe and having a bore, tubing extending from the interior of the well pipe through said tubing hanger, means 10 for supporting said tubing within said bore, a shoulder arranged in said bore, packing means surrounding said tubing and resting on said shoulder, an elongated member extending into the upper end of the tubing hanger and having 15 its lower end engaging the packing to clamp the packing between said member and said shoulder, said elongated member having a vertical bore extending axially therethrough and communicating with said tubing, an arm extending laterally from said member and having a horizontal passageway communicating with said vertical bore, a seat within the upper end portion of said elongated member extending inwardly from the wall of said vertical bore and arranged at the inner end of said horizontal passageway, and a sealing member arranged within the upper end portion of said elongated member 20 and rockably supported on said seat for sealing the upper end portion of said vertical bore.
2. In combination, a well pipe, a tubing hanger secured to the upper end of the well pipe and having a bore, tubing extending from the interior of the well pipe through said tubing hanger, means 25 for supporting said tubing within said bore, a shoulder arranged in said bore, packing means surrounding said tubing and resting on said shoulder, an elongated member extending into the upper end of the tubing hanger and having 30 its lower end engaging the packing to clamp the packing between said member and said shoulder, said elongated member having a vertical bore extending axially therethrough and communicating with said tubing, an arm extending laterally from said member and having a horizontal passageway communicating with said vertical bore, a seat within the upper end portion of said elongated member extending inwardly from the wall of said vertical bore and means for sealing the upper end portion of said vertical bore, said means including an elongated sleeve extending 35 into said elongated member and having its lower end rockably supported on said seat.
3. In combination, a well pipe, a tubing hanger secured to the upper end of the well pipe and having a bore, tubing extending from the interior of the well pipe through said tubing hanger, means 40 for supporting said tubing within said bore, a shoulder arranged in said bore, packing means surrounding said tubing and resting on said shoulder, an elongated member extending into the upper end of the tubing hanger and having 45 its lower end engaging the packing to clamp the packing between said member and said shoulder, said elongated member having a vertical bore extending axially therethrough and communicating with said tubing, an arm extending laterally from said member and having a horizontal passageway communicating with said vertical bore, a seat within the upper end portion of said elongated member extending inwardly from the wall of said vertical bore, and a sealing member arranged within the upper end portion of said vertical bore, said sealing member having its lower end in substantial alignment with the upper portion of said horizontal passageway.
4. In combination, a well pipe, a tubing hanger secured to the upper end of the well pipe and having a bore, tubing extending from the interior of the well pipe through said tubing hanger, means 50 for supporting said tubing within said bore, a shoulder arranged in said bore, packing means surrounding said tubing and resting on said shoulder, an elongated member extending into the upper end of the tubing hanger and having 55 its lower end engaging the packing to clamp the packing between said member and said shoulder, said elongated member having a vertical bore extending axially therethrough and communicating with said tubing, an arm extending laterally from said member and having a horizontal passageway communicating with said vertical bore, a seat within the upper end portion of said elongated member extending inwardly from the wall of said vertical bore, and a sealing member arranged within the upper end portion of said vertical bore, said sealing member having its lower end in substantial alignment with the upper portion of said horizontal passageway.
5. In combination, a well pipe, a tubing hanger secured to the upper end of the well pipe and having a bore, tubing extending from the interior of the well pipe through said tubing hanger, means 60 for supporting said tubing within said bore, a shoulder arranged in said bore, packing means surrounding said tubing and resting on said shoulder, an elongated member extending into the upper end of the tubing hanger and having 65 its lower end engaging the packing to clamp the packing between said member and said shoulder, said elongated member having a vertical bore extending axially therethrough and communicating with said tubing, an arm extending laterally from said member and having a horizontal passageway communicating with said vertical bore, a seat within the upper end portion of said elongated member extending inwardly from the wall of said vertical bore, and a sealing member arranged within the upper end portion of said vertical bore, said sealing member having its lower end in substantial alignment with the upper portion of said horizontal passageway.
6. In combination, a well pipe, a tubing hanger secured to the upper end of the well pipe and having a bore, tubing extending from the interior of the well pipe through said tubing hanger, means 70 for supporting said tubing within said bore, a shoulder arranged in said bore, packing means surrounding said tubing and resting on said shoulder, an elongated member extending into the upper end of the tubing hanger and having its lower end engaging the packing to clamp the packing between said member and said shoulder, said elongated member having a vertical bore extending axially therethrough and communicating with said tubing, an arm extending laterally from said member and having a horizontal passageway communicating with said vertical bore, a seat within the upper end portion of said elongated member extending inwardly from the wall of said vertical bore, and a sealing member arranged within the upper end portion of said vertical bore, said sealing member having its lower end in substantial alignment with the upper portion of said horizontal passageway.

JAMES B. WRIGLEY.
